(57) CLAIM

The ornamental design for a bathtub with feet, as shown and described.

DESCRIPTION

FIG. 1 is an overall perspective view of a bathtub with feet; FIG. 2 is a front side view of the bathtub with feet of FIG. 1;

FIG. 3 is a rear side view of the bathtub with feet of FIG. 1; FIG. 4 is a right side view of the bathtub with feet of FIG. 1, wherein the left side view is identical; and,

FIG. 5 is a top plan view of the bathtub with feet of FIG. 1. All broken lines represent portions, structure, or features of the bathtub with feet that are included for the purposes of illustration only and form no part of the claimed design.
